UNITED STATES PATENT OFFICE.

TOUSSAINT BICHEROUX, OF DUSSELDORF, GERMANY.

METHOD OF AND APPARATUS FOR THE MANUFACTURE OF IRON RAILS, &c.

SPECIFICATION forming part of Letters Patent No. 470,466, dated March 8, 1892.

Application filed September 7, 1891. Serial No. 404,990. (No model.)

To all whom it may concern:

Be it known that I, TOUSSAINT BICHEROUX, a subject of the King of Belgium, residing at Dusseldorf-on-the-Rhine, Prussia, German

5 Empire, have invented new and useful Improvements in Methods of and Apparatus for the Manufacture of Rails, Girders, and Rolled Bars of Various Sections and Similar Objects, of which the following is a specification.

10 My invention has reference to an improved method of and apparatus for manufacturing rolled-iron rails, joists, beams, bars, and the like of various cross-sections; and it has for its object to simplify the rolling-plant and to 15 permit the bases, flanges, or other parts of the rolled irons to be enlarged beyond the limits to which they are confined by the present methods.

My invention consists, essentially, in preparing a blank (pile or ingot) of approximately 20 rectangular cross-section, forming into said blank a longitudinal groove corresponding in depth to the desired width of flanges or base, rolling said grooved blank to approximately 25 the required cross-section with the flanges pressed together, then opening and spreading the flanges to the required degree, and finally 30 finishing the iron, all of which is more fully pointed out in the following specification and 35 claims, the apparatus being illustrated in the accompanying drawings, in which—

Figure 1 represents a sectional front elevation of a train of rolls for rolling the pile and for grooving the same. Fig. 2 is a similar 35 view of the trains for shaping the blank and for finishing the same. Fig. 3 is a sectional side elevation of the spreading apparatus. Fig. 4 is a sectional plan. Fig. 5 is a section in the plane $y-y$, Fig. 3. Fig. 6 is a sectional 40 end elevation of a modified form of spreading apparatus. Figs. 7 to 15 show cross-sections of several forms of irons in the successive stages of their manufacture. Fig. 16 is a sectional elevation of a spreading apparatus 45 adapted for the construction of the irons shown in Fig. 8. Fig. 17 is a sectional front elevation of an apparatus for bending the flanges of the rails shown in Fig. 8. Figs. 18 and 19 are end elevations showing the trains 50 for rolling the bars shown in Figs. 9 and 10. Fig. 20 is a sectional plan of the apparatus for spreading the flanges of the bar shown in

Figs. 9 and 10. Fig. 21 is an end view of the same. Fig. 22 represents a finished rail of particular form.

55

Similar letters and figures indicate corresponding parts throughout the several views.

In carrying out my invention—for instance, in the manufacture of railroad-rails—the pile or ingot is reduced to the required rectangular cross-section by passes 1 to 12 of rolls A, B, C, D, E, and F, Fig. 1, all as usual. A longitudinal groove is then rolled into the blank to a depth to correspond to the required width of base on the finished rail by passes 13 and 60 14 through rolls D E F. When an ingot is used, the groove may be cast therein prior to passing it through the rolls. After passes 13 14 have been made the blank is passed through 65 15 and 16 of rolls D E F and then through 70 the successive passes of rolls J, K, and L, Fig. 2, where it is finally brought to approximately 75 the required cross-section, the portions of the blank adjacent to the groove, which subsequently form the base of the rail, being pressed together. However, it is to be understood that no welding takes place.

The next step consists in spreading open and flattening out the portions or flanges adjacent to the grooves to form the base, which 80 may be done by the apparatus shown in Figs. 3, 4, and 5. Referring to said figures, the frame a of the finishing-rolls b has affixed thereto a bed-plate c , containing horizontal ways for a carriage d , mounted to move toward and from the finishing-rolls. To hold the rail on the carriage and to prevent the cross-section of the head and web from being 85 distorted during the spreading of the base, a bracket f is secured to the carriage and provided with an interchangeable facing g , against which the head of the rail bears. The web is engaged from above by a lug h on a cross-head h and from below by the plunger i of a hydraulic cylinder i' .

95

To spread the parts to form the base of the rail, a wedge, as k^2 , is provided, which is forced between the said parts by the plunger k of a hydraulic cylinder k' . After the wedge has been forced between the parts the carriage d is moved toward the finishing-rolls b , preferably by means of a hydraulic cylinder l , to start the spreading and to conduct the rail to said rolls. The rolls drawing the rail

100

forward, the flanges are opened by the wedge and finally flattened out by the said rolls.

In Fig. 6 I have shown the hydraulic cylinders dispensed with and a train of rolls substituted, *m* representing the rolls for finishing the head and web, in front of which is mounted a shaft *n*, carrying three rolls *o*, *p*, and *q*, operating in conjunction with the rolls *m*, the one *o* shaping the upper sides of the flanges or parts which form the base, the second *p*, which is made conical, opening and spreading the said parts, and the third *q* finishing the base. It is evident that the same method can be equally well applied to the manufacture of bars, beams, joists, and the like, several forms of which I have illustrated in the drawings.

In Fig. 7 the steps in the process of rolling ordinary railway-rails with narrow bases are illustrated.

In Fig. 8 I have shown a rail with a very broad base. For spreading the parts to form the base in this class of rails the apparatus illustrated in Fig. 16 is made use of, which corresponds in general to that described in Figs. 3, 4, and 5. When a rail of this description is to embrace a longitudinal sleeper, the two parts of the flanges of the base are bent or curved downward, as shown in Fig. 8 at *f*. The apparatus shown in Fig. 17 is constructed for this purpose, and consists of a roll *s*, mounted in a frame *r*, and having two rolls *s' s'* mounted at right angles thereto in a frame *w*. Motion is conveyed from a shaft *u* to the roll *s* by gear-wheels *t t* and to the rolls *s' s'* by gear-wheels *v v'*. Heretofore such rails were made in two parts; but by my new method I am enabled to make the same in one piece.

In Fig. 9 I have illustrated the manufacture of **I** and **H** iron girders, and in Fig. 10 the same, but of larger dimensions. For rolling these girders the trains shown in Figs. 18 and 19 are used, the same consisting of rolls *L'* for grooving the blank and rolls *M'* for shaping the same. The upper and lower rolls are made adjustable in the usual manner, six rolls answering to reduce the blank to the proper cross-section prior to spreading the flanges. For the latter operation the apparatus shown in Figs. 20 and 21 is employed, the same being similar to that shown in Figs. 3, 4, and 5, but having the spreading devices in duplicate, so as to spread both flanges at one and the same time.

Fig. 11 illustrates the production of angle-iron; Fig. 12, **T**-iron; Fig. 13, cross-iron; Fig. 14, channel-iron, and Fig. 16 **Z**-iron.

In the manufacture of channel and **Z** irons, Figs. 14 and 15, the lines where the metal is to be bent, as along the sides *a' b'*, are reinforced by small longitudinal beads or ribs *c'*.

In Fig. 22 I have shown a railway-rail having its base widened out at the points where it rests upon the ties or sleepers. In producing this highly-useful form the faces of the

finishing-rolls for spreading and shaping the flanges are recessed where the widening takes place. The circumference of the rolls must therefore be equal to the distance between the centers of the widened parts.

The apparatus illustrated in Fig. 6 is shown as adapted for producing this form of rail.

I do not wish to confine myself to any particular means for forming the blank, for forming the groove into the same, or for imparting the required cross-section to the finished rail.

What I claim as new, and desire to secure by Letters Patent, is—

1. The method of manufacturing rails, beams, and other irons, which consists in forming a blank (pile or ingot) of the proper dimensions provided with a longitudinal groove, reducing the grooved blank to the desired cross-section, and spreading the grooved portions or flanges, substantially as described.

2. The method of manufacturing rails, beams, and other irons, which consists in forming a blank (pile or ingot) of substantially rectangular cross-section, providing the blank with one or more longitudinal grooves, reducing the grooved blank to the desired cross-section, and finally spreading out the grooved portions or flanges and finishing the iron, substantially as described.

3. The method of manufacturing rails, beams, and other irons, which consists in first forming a blank approximately rectangular in cross-section by rolling, forging, or casting, then rolling a longitudinal groove into the blank corresponding to the cross-section to be produced in the finished iron, then passing the blank through successive rolls until the cross-section is approximately that desired with the flanges pressed together, then spreading the flanges apart, and finally finishing the iron by rolling, substantially as described.

4. In a rolling-mill, a train of rolls for reducing the grooved blank, (pile or ingot,) a device for spreading the grooved portion to form flanges, and rolls for widening out the flanges, substantially as described.

5. In a roller-mill, a train of rolls for reducing the blank, (pile or ingot,) means for forming a longitudinal groove into the same, and a device for spreading the grooved portion, substantially as described.

6. In a roller-mill, a train of rolls for reducing the blank, (pile or ingot,) means for forming a longitudinal groove into the same, a device for spreading the grooved portion, and finishing-rolls, substantially as described.

7. In a roller-mill, a train of rolls for reducing the blank, (pile or ingot,) means for forming a longitudinal groove into the same, a device for spreading the flanges, and recessed rolls for locally widening the flanges, substantially as described.

8. In a mill, an apparatus for opening and spreading the grooved blank, consisting of a wedge, a hydraulic cylinder arranged to force

the wedge into the groove, a device for holding the iron, and a pair of rolls or other device for drawing the iron forward, substantially as described.

5 9. The method of manufacturing sleeper-rails, which consists in forming a blank (pile or ingot) of the proper dimensions, providing the blank with a longitudinal groove, reducing the grooved blank to the desired cross-
10 section, spreading the grooved portions or

flanges, and then turning the same down, substantially as described.

In testimony whereof I have signed my name to this specification in the presence of two subscribing witnesses.

TOUSSAINT BICHEROUX.
